UNITED STATES PATENT OFFICE.

WILLIAM MACH, OF TABOR, SOUTH DAKOTA.

WELL-TILING AND MOLD THEREFOR.

1,036,867.

Specification of Letters Patent. Patented Aug. 27, 1912.

Application filed January 5, 1912. Serial No. 669,656.

To all whom it may concern:

Be it known that I, WILLIAM MACH, a citizen of the United States, residing at Tabor, in the county of Bonhomme, State of 5 South Dakota, have invented certain new and useful Improvements in Well-Tiling and Molds Therefor; and I do hereby declare the following to be a full, clear, and exact description of the invention, such as 10 will enable others skilled in the art to which it appertains to make and use the same.

This invention relates to well tiling and mold therefor.

The object of the invention resides in the 15 provision of a mold through the instrumentality of which a section of well tiling may be constructed of such a nature that said sections may coöperate with suitable guide wires in the lowering of the sections 20 into the well so as to assure the proper positioning of the sections one upon the other.

With the above and other objects in view, the invention consists in the details of construction and in the arrangement and combination of parts to be hereinafter more 25 fully described and particularly pointed out in the appended claims.

In describing the invention in detail, reference will be had to the accompanying 30 drawings wherein like characters of reference denote corresponding parts in the several views, and in which—

Figure 1 is a view in elevation of a mold utilized to construct the sections of the 35 tiling, Fig. 2, a vertical section of the mold illustrated in Fig. 1, Fig. 3, a section on the line 3—3 of Fig. 1, Fig. 4, a view in elevation of the inner side section of the mold, same being partly broken away, Fig. 5, a 40 vertical section through one of the tile sections produced by the mold, Fig. 6, a section on the line 6—6 of Fig. 5, Fig. 7, a view showing the manner of applying the tile sections to a well, said tile sections being 45 shown in vertical sections, and Fig. 8, a section on the line 8—8 of Fig. 7 on an enlarged scale.

Referring to the drawings the mold is 50 shown as comprising a bottom 10 having a central dished portion 11, said dished portion having a circular outline. Formed in the bottom of the dished portion 11 is a circular groove 12, while another circular groove 13 is formed in the upper face of the

body just outward of the dished portion 55 11 and disposed concentrically with the groove 12. These grooves 12 and 13 form seats respectively for inner and outer side sections 14 and 15 respectively of the mold. The inner side section 14 is constructed of 60 a thin sheet of metal of sufficient pliability to permit same to be contracted from its normal position for the purpose of removing same after the molding of the tile section has been completed. When the inner 65 side section 14 is seated in the groove 12 the ends of said section are secured together by means of suitable catches 16. The outer side section 15 is also constructed of a thin sheet of metal of sufficient pliability to permit the ends thereof to be moved away from each other a sufficient distance to allow for the removal of said side section from the completed tile section. This outer side section 15 has pressed in its inner face at the 70 top and bottom thereof respectively circumscribing grooves 17 and 18. Formed in the side section 15 in the plane of the groove 17 is a plurality of openings 19. These openings 19 at the top and bottom respectively of 75 the outer side sections are arranged in vertically alined pairs with the vertical plane of the other pair. The outer side section 15 is further provided with a plurality of openings 20 in the plane of the groove 18 and 80 are disposed in a manner similar to the openings 19. Surrounding each of the openings 19 is an inwardly directed flange 21, while similar inwardly directed flanges 22 surround each of the openings 20. The 85 ends of the sections 15 are detachably secured together by means of suitable catches 23.

Hinged to the upper end of the section 15 is the top member of the mold 24. This top 90 member is provided centrally with a boss 25 of a shape that would permit same to snugly fit in the dished portion 11 of the bottom 10. The top 24 is adapted to be operated from open to closed position and vice versa by 95 means of a handle 26 secured thereto and projecting laterally therefrom. Pivoted upon this handle 26 is a hook 27 adapted to detachably engage a lug 28 on the outer section 15 to secure the top in closed position. 100

In the use of the mold the sections 14 and 15 are seated in respective grooves 12 and 13 of the bottom 10, the catches 16 and 23 having

been previously operated to locking position. The material for the tile section, indicated at 29, is then deposited in a plastic form between the sections 14 and 15. A liberal supply of this material is deposited so that when the top 24 is closed the boss 25 of the latter will shape the upper end of the section so as to readily receive in an interfitting manner the lower end of an adjacent 10 section. While the material of the tile section 29 is in a plastic state staples 30 are inserted through the openings 19 and 20 into the plastic material so that the outermost portion of said staples will be positioned in registration substantially with the innermost portions of respective grooves 17 and 18. After the material from which the tile section is made has solidified the catches 16 and 23 are released and the sections 14 20 and 15 removed from the completed tile section, as is likewise the bottom 10.

In applying the tile sections to the bore of a well suitable guide wires 31 are passed through alining staples 30 of the bottom 25 sections and then positively secured to the latter at its lower end. The section of the tile is then lowered to its seat upon the bottom of the well. The guide wires 31 are then passed through alining staples 30 of the next tile section and the latter then lowered under the guidance of said wires 31 to its proper position upon the tile section disposed therebeneath. In this manner all 35 the tile sections desired may be placed in the bore of the well with absolute assurance that they are correctly positioned one upon the other. It will be noted that by reason of the grooves 17 and 18 the tile sections will be formed with circumscribing ribs 32 which 40 serve to protect the staples 30 from engagement with the wall of the well during the lowering of the tile section.

What is claimed is:

1. A well tile mold comprising a bottom provided with concentrically arranged circular grooves, longitudinally split inner and outer cylindrical side sections removably seated in said grooves respectively, locking means for detachably securing the longitudinal edges of said side sections together, 45 said outer side section having continuous circular grooves formed in its inner face adjacent its top and bottom respectively and openings therethrough in the planes of respective grooves, the openings at the upper 50 ends of said outer side section alining with corresponding openings at the lower ends thereof respectively, and a top member for said mold hinged to said outer side section.

2. A well tile mold comprising a bottom 60 provided with concentrically arranged circular grooves, longitudinally split inner and outer cylindrical side sections removably seated in said grooves respectively, locking means for detachably securing the longitudinal 65 edges of said side sections together, said outer side section having continuous circular grooves formed in its inner face adjacent its top and bottom respectively and further openings therethrough in the planes 70 of said grooves respectively, the openings at the upper ends of said outer side sections alining with corresponding openings at the lower ends thereof respectively, inwardly directed flanges surrounding each of said 75 openings, and a top member for said mold hinged to said outer side section.

In testimony whereof, I affix my signature, in presence of two witnesses.

WILLIAM MACH.
